United States Patent Office

Des. 195,527
Patented June 25, 1963

195,527

SILVERWARE HOLDER

Nathaniel Gilbert, 1075 1st Ave., New York, N.Y.

Filed Jan. 2, 1962, Ser. No. 68,141

Term of patent 3½ years

(Cl. D44—29)

Fig. 3

FIG. 1 is a top plan view of a silverware holder constructed according to the invention;

FIG. 2 is a sectional view taken on line 2—2 of FIG. 1; and

FIG. 3 is a side elevational view thereof.

I claim:

The ornamental design for a silverware holder, as shown.
